ILLUMINABLE STEAK MARKER

Clarence E. Johnson, 1804 S. Lincoln, and Gilbert P. Erickson, 1522 Linda Lane, both of Aberdeen, S. Dak. 57401

Filed Sept. 10, 1965, Ser. No. 86,931

Term of patent 3½ years

(Cl. D72—1)

FIG. 1

FIG. 2

FIG. 3

FIGURE 1 is a front elevational view of the illuminable steak marker showing our new design.

FIGURE 2 is a top plan view thereof.

FIGURE 3 is a bottom plan view thereof.

The dominant features of our design reside in the portions shown in full lines.

We claim:

The ornamental design for an illuminable steak marker, substantially as shown and described.
